UNITED STATES PATENT OFFICE

JOHN G. GORGEN, OF NEW YORK, N. Y.

METER-SEAL.

1,159,211.

Specification of Letters Patent.

Patented Nov. 2, 1915.

Application filed December 1, 1914. Serial No. 874,982.

To all whom it may concern:

Be it known that I, JOHN G. GORGEN, a subject of the Emperor of Germany, and a resident of the city of New York, borough of 5 Manhattan, in the county and State of New York, have invented a new and Improved Meter-Seal, of which the following is a full, clear, and exact description.

This invention relates to improvements in 10 seals, and has for an object to provide an improved construction which will readily disclose the fact that the same has been tampered with when an unauthorized person attempts to open the same.

15 Another object of the invention is to provide a seal for a meter which must be destroyed by either an authorized or an unauthorized person before the meter can be opened.

20 In the accompanying drawings—Figure 1 is a plan view of the meter and a suitable support therefor, a seal embodying the invention being applied to the meter; Fig. 2 is a longitudinal vertical section through 25 the seal shown in Fig. 1, the same being on an enlarged scale; Fig. 3 is a view similar to Fig. 2, but showing the sealing wire as twisted and cut off; Fig. 4 is a section through Fig. 3 on line 4—4.

30 Referring to the accompanying drawings by numerals, 1 indicates any desired support for a meter 2, which meter is held closed by suitable members 3 and 4, which members may be of any desired construction, as for 35 instance with a threaded portion acting as a nut for holding the face of the meter in position, and with a looped or yoke portion for receiving links 5 and 6. The links 5 and 6 are designed to extend into the seal 7 and be 40 held therein by a suitable wire 16 which seals or positively locks the links against removal. As shown in Figs. 2 to 4, inclusive, the seal is formed with a body 8 having passageways 9 and 10 converging into a single 45 passageway 11. Associated with the body 8 is a cap 12 provided with a passageway 13, the ends of which register with the passageways 9 and 10. Wire 16 is threaded through the passageway 13 in cap 12 and then 50 through suitable openings in the links 5 and 6 after which the ends of the wire are forced through the passageways 9 and 10 and then out passageway 11. The protruding ends of the wire are clamped by a suitable mem-

ber, as for instance a pair of pliers and 55 twisted so as to appear as shown in Fig. 3, after which the surplus wire is cut off.

When the wire is twisted as shown in Fig. 3, the same substantially fills the passageway 11, and thus prevents the insertion of 60 any tool at this point, either for unwinding the wire or permitting access to any of the interior parts. In order to prevent the insertion of a saw or other instrument between the body 8 and cap 12, the body 8 is provided 65 with side flanges 14 and 15 (Fig. 4) which overlap to any desired extent the cap 12. By this construction and arrangement the wire 16 cannot be removed without breaking or mutilating to an appreciable extent 70 either body 8 or cap 13 so that it can be readily observed whenever anyone tampers with the seal. When an authorized person desires to open the meter it is necessary for him to break the seal, and after the seal has 75 been broken the meter may be easily opened for inspection, repair or other purpose. A new seal must then be provided as the old seal cannot be used but once. The material of which body 8 and cap 12 is made is pref- 80 erably of some fragile material, as for instance porcelain so that the same may be easily broken but sufficiently strong to hold the parts together unless force is applied thereto.

85

What I claim is—

1. In a seal of the class described, a fragile body having a passageway therethrough, a fragile cap having a passageway therethrough, and a locking wire extending 90 through the passageways in said cap and said body, said locking wire being twisted for preventing removal and said locking wire being adapted to hold a pair of combined supporting and locking links in place, 95 said links being arranged with one end between said body and said cap.

2. In a seal of the class described, a body of fragile material, said body having a pair of passageways extending partly therethrough and then merging into a single passageway, a cap arranged in the top of said body formed with a single passageway, the ends of which are adapted to register with said pair of passageways, and a wire ex- 100 tending through all of said passageways for holding in place a pair of supporting and locking links, said wire being twisted where 105

the same is arranged in said outlet and said links being arranged with one end between said body and said cap.

3. In a seal of the class described, a body 5 having an outlet passageway merging into a pair of diverging passageways, said body being formed on each side with a flange, a cap adapted to fit against said body between said flanges, said cap having a single passageway with the ends registering with said diverging passageways, and a wire threaded 10 through said passageways and arranged

with the ends adjacent the outer end of said outlet passageway, said wire being adapted to hold a pair of combined supporting and locking links in place.

In testimony whereof I have signed my name to this specification in the presence of two subscribing witnesses.

JOHN G. GORGEN.
